[57] CLAIM

The ornamental design for a shoulder carrying strap for a bag, as shown and described.

DESCRIPTION

FIG. 1 is a left side elevational view of a shoulder carrying strap for a bag showing my new design;

FIG. 2 is a bottom plan view of the shoulder carrying strap of FIG. 1;

FIG. 3 is a front elevational view thereof;

FIG. 4 is a rear elevational view thereof;

FIG. 5 is a top plan view of the shoulder carrying strap of FIG. 1; and,

FIG. 6 is a partial cross sectional view taken along the lines VI—VI showing a tapering thickness of a shoulder portion of the strap.

FIG. 2

FIG. 3

FIG. 4

FIG. 1

FIG. 5

FIG. 6
